PNEUMATIC POWER TOOL FOR APPLYING FASTENERS

Clarence V. Le Sage, 1333 N. Baker St., Stockton, Calif.,
and Arthur Raisch, 261 Barden Road, Bloomfield Hills,
Mich.

Filed Aug. 13, 1962, Ser. No. 71,271

Term of patent 14 years

(Cl. D54—14)

FIG. 1

Des. 195,591

PAGE 2

FIG. 3

FIG. 5

FIG. 6

FIG. 7

FIG. 8

FIG. 1 is a perspective view of a pneumatic power tool for applying fasteners, showing our new design.

FIG. 2 is a side elevational view thereof, the opposite side being substantially the same in appearance.

FIG. 3 is a bottom plan view thereof.

FIG. 4 is a sectional view taken along the section line 4-4 of FIG. 2.

FIG. 5 is a top plan view thereof.

FIG. 6 is an elevational view taken from the left side of FIG. 2.

FIG. 7 is a sectional view taken along the section line 7-7 of FIG. 5.

FIG. 8 is an elevational view taken from the right side of FIG. 2.

We claim:

The ornamental design for a pneumatic power tool for applying fasteners, substantially as shown and described.
